Howson and Howson.

UNITED STATES PATENT OFFICE

2,399,065

ELECTROMAGNETIC SWITCH COIL
MOUNTING

Harold E. Schleicher, West Hartford, Conn., assignor to The Arrow-Hart & Hegeman Electric Company, Hartford, Conn., a corporation of Connecticut

Application March 24, 1941, Serial No. 385,024

1 Claim. (Cl. 175—341)

This invention relates to electric switch devices operable by an electromagnet. More particularly, the invention relates to a novel construction of certain parts of an electromagnetic switch, with particular reference to the means for mounting the electromagnet coil.

It is an object of the invention to provide a simple and inexpensive mounting means for the electromagnet coil, whereby the coil may be quickly placed and firmly held in position when the device is assembled, and may be readily removed for repairs or replacement, as occasion arises.

Other objects and advantages of the invention will become apparent as it is described in connection with the accompanying drawing.

In the drawing—

Fig. 1 is an end elevation view, partly broken away, of a device embodying the invention.

Fig. 2 is a plan view of the electromagnet assembly, partly broken away.

Fig. 3 is a detail view showing in perspective one section of the core of the electromagnet, with the coil mounting means attached thereto, but with the coil removed.

Referring to the drawing, the operating parts are mounted upon a stamped sheet metal back or base plate 10, which is substantially rectangular in form. Bridging contact members may be carried in insulated relation by a movable insulating block 24 mounted upon a sheet metal frame in convenient fashion. One satisfactory manner of mounting is illustrated in the co-pending application of Magnus G. Dahl, Serial No. 200,997, filed April 8, 1938, issued as Patent No. 2,283,795 on May 19, 1942. The frame for carrying the movable contact block 24 may comprise a pair of flat parallel side bars 26a and 26b. These side bars are joined on one end by a transverse bar on which the movable contact-carrying insulating block is mounted.

For the purpose of supporting the side bars 26a and 26b and the stationary core or field piece of the electromagnet, there are provided a pair of complementary stamped sheet metal supporting members, designated generally by the numerals 32 and 34. These members have flat flange portions or feet 32a and 34a, resting upon and secured, preferably by welding, to the back plate 10 adjacent its side edges and at the opposite end from the stationary contact block 12. Bent up perpendicularly from the feet of the members 32 and 34 are side plate portions 32b and 34b. The upper portions 32c and 34c of said side plate portions are offset outwardly at one end to provide room for the movement of the side bars 26a and

26b. To guide the movement of the outer ends of the side bars 26a and 26b, slots 36 running parallel to back plate 10 are provided in the offset portions 32c and 34c running parallel to the back plate, and the slots receive pins 38 that extend laterally from the end portions of the bars 26a and 26b. Alternatively, instead of pins, ribs may be pressed out laterally and parallelly from the end portions of the bars to slide in the slots

10 36. The opposite ends of the bars 26a and 26b are pivotally supported by the parallel arms 30a and 30b of a U-shaped or yoke member 30. This member is pivotally mounted on an axle rod 31 passing through side plates 32b and 34b and 15 through the arms 30a and 30b adjacent and parallel to the transverse portion of the member 30.

In order to support the E-shaped laminated stationary field piece 44 of the electromagnet, lugs 32d and 34d are bent inwardly from the side 20 plates 32b and 34b parallel to the back plate 10 near the inner end (the upper end in Fig. 2). The field piece 44 is secured to the lugs 32d and 34d by bolts 46 which may also serve to secure the sheet metal stamping or support 90 for other 25 devices which may be used in connection with the invention.

For the purpose of supporting and carrying the armature 40 of the electromagnet, there are provided ears 26c which are bent inwardly from the 30 lower edge of the outer (lower) ends of the side bars 26a and 26b (see Fig. 2). The armature 40 may be of E-shape, and may be secured to the ears 26c by a pair of bolts 42.

For quick and accurate positioning of the armature and field piece, bosses, such as 26g and 32g, may be provided around the holes into which the bolts 42 and 46 thread. These may be formed by pressing up the edges of the holes as the holes are punched. The bosses will be received in enlargements at the ends of the passages in the armature and field pieces through which the bolts 42 and 46 pass.

The electromagnet coil 50 is manufactured as a unit, which may be assembled upon and moved from the central arm of the field piece or core 44 of the electromagnet. For supporting this coil, there are provided a pair of channel-shaped guides 52 facing each other and secured to the top and bottom of the central arm of the 50 field piece 44. These channel-shaped guides are preferably made of non-magnetic material and have cut into their free ends a pair of longitudinal slots 52a forming a central resilient finger 52b whose end is bent perpendicularly 55 thereto, toward the coil. In order that the coil

may be readily mounted upon the guides 52 with the guides extending through the coil aperture and held in position when mounted thereon, and may be readily removable therefrom, the guides are preferably made of material which is thin enough and resilient enough to permit flexing inwardly of the resilient fingers 52b to permit passage of the coil over the outwardly-bent ends 52c. It may readily be observed from the foregoing description that when the coil is put in place, the resilient fingers will snap in position so that their outwardly-bent ends 52c will engage the edge of the coil to hold it in assembled position. Conversely, the fingers 52b may be pressed toward each other to permit the coil to be removed.

It may now be observed that in order to repair or replace the coil 50, it is only necessary to remove the movable armature 40 of the electromagnet core by unscrewing the two bolts 42 and then pressing together the resilient fingers 52b of the guides sufficiently to permit the coil to be pulled off the guides. It is not, however, necessary to remove the operating assembly in order to get at and remove the coil of the magnet, since the coil can be removed as soon as the movable core has been detached from its mounting. The coil can be moved axially underneath the stamping 90 which customarily supports other parts (not shown) of the electromagnetic switch, without moving that stamping. 30

This stamping may be of channel-shape, with wing portions 90a and 90b bent outwardly from the sides in position to lie upon the top surface of the stationary field piece 44. Apertures are provided in the wing portions to register with similar apertures in the stationary core 44 and to receive the bolts 46 so that the stamping and all parts carried thereby may be held upon the field piece by the two bolts 46.

10 Many modifications within the scope of the invention will occur to those skilled in the art. Therefore, I do not limit the invention to the exact details of the embodiments as illustrated and described.

15 I claim:

In an electromagnetic switch, a laminated field piece, an armature, armature guide means mounted on said field piece, a coil axially mountable on said field piece, said guide means comprising a non-magnetic member having portions at least partly embracing and guiding said armature and having slots forming a resilient finger with means on the end thereof to hold said coil against removal axially from said guide means, 20 said finger being resiliently flexible to permit disengagement and removal of said coil from said guide means.

HAROLD E. SCHLEICHER.
